DESIGN FOR AN ELECTRIC HAND LANTERN

Alfred C. Korte, St. Louis, Mo., assignor to
Metalcraft Corporation, St. Louis, Mo., a cor-
poration of Missouri

Application February 26, 1934, Serial No. 50,859

Term of patent 7 years

To all whom it may concern:

Be it known that I, ALFRED C. KORTE, a citizen of the United States, residing at St. Louis, in the State of Missouri, have invented a new, original, and ornamental Design for Electric Hand Lanterns, of which the following is a specification, reference being had to the accompanying drawings forming parts thereof.

Referring to the drawings:

Figure 1 is a side elevation of an electric hand lantern, showing my new design.

Figure 2 is an inverted plan view of an electric hand lantern, showing my invention.

I claim:

The ornamental design for an electric hand lantern, substantially as shown.

Signed at St. Louis, in the State of Missouri this 22 day of February, 1934.

ALFRED C. KORTE.
